UNITED STATES PATENT OFFICE.

ARTHUR G. SCHLOSSER AND WILMER N. ELTON, OF GRAND FORKS, NORTH DAKOTA.

METHOD AND MEANS FOR STRENGTHENING OR REENFORCING GUNSTOCKS.

Application filed July 27, 1923. Serial No. 654,232.

To all whom it may concern:

Be it known that we, ARTHUR G. SCHLOSSER and WILMER N. ELTON, citizens of the United States, residing at Grand Forks, in the county of Grand Forks and State of North Dakota, have invented certain new and useful Improvements in Methods and Means for Strengthening or Reenforcing Gunstocks, of which the following is a specification.

This invention relates to a method and means for strengthening or reenforcing gun stocks.

Gun stocks wherein the stock and fore-arm are made from a single piece of wood, instances of which are modern bolt action, sporting, and military rifles, have a tendency in time, to split at the small of the grip due to effect of the force of the recoil. In the United States Army rifle, 1903 model, which is the particular arm with which we have shown our invention combined, the weakest point is where the rear guard screw passes through the stock for the purpose of fastening the guard to the receiver and in illustrating a practical embodiment of our invention as we have used this rifle by way of example, the invention is disclosed as adapted thereto.

In applying the invention to rifles of other design, modification may be resorted to to adapt the reinforcement to the particular type of arm to the end that the recoil will be distributed through the reinforcement and its connections over a large area of the stock to prevent splitting at vulnerable points.

In carrying out our method, parallel cuts are made through, and lengthwise of the stock, preferably from the magazine opening, backwardly through the small of the grip into the solid part of the stock. These cuts may be made by a saw or by any other means suitable for the purpose. Having previously prepared the stock in this fashion, a plurality of plates of suitable thickness and preferably of steel, are inserted in the cuts. Preferably, two plates of duplicate form will be used, such plates being suitably shaped with straight and curved parts and abutment edges so that when the rifle action is assembled to the stock, the forward end of the plates abut

the magazine, the lower part of the receiver fits tightly between the upper edges of the plates and to the rear of the receiver the edges of the plates are flush with the wood of the stock. The guard fits tightly between the lower edges of the plates and said edges are at this point flush with the wood of the stock; the rear edges of the plates are disposed in the solid part of the stock back of the grip and, preferably, abutting a part of the stock.

The next step is to rivet the plates to the stock which is accomplished by first drilling transversely through the stock and the re-enforcing plates at suitable points and then passing rivets therethrough and securing them.

While any desired number of rivets may be used, they are, preferably, so located in relation to the rifle action when the latter is assembled to the stock that the rivets tend to firmly anchor the plates to the rifle action and to so connect the plates to the grip part of the stock that they will strengthen and stiffen it at its weakest point. To that end, it is preferable to place a rivet immediately to the rear of the guard screw and another to the rear of the magazine because at these points the wood of the stock is compressed. The remaining rivet may be located at the rearmost parts of the plates to assist in taking up the recoil which would otherwise be taken by the stock.

It is to be understood that while we have illustrated our invention in connection with the United States Army rifle model of 1903 and have disclosed reenforcing plates and rivets adapting the invention to that particular arm, this is not by way of limitation of the invention as modification will necessarily be resorted to according to the design of which the invention is used. So far as we are aware, we are the first to reinforce the stock of a firearm by the provision of one or more plates, and cross connections, contained therein and, more specifically, by cutting one or more kerfs or slots in the stock, then inserting one or more reenforcing plates, and finally securing the plate or plates to the stock whether by cross drilling and the insertion of rivets, or otherwise.

In the accompanying drawings: Figure 1 is a side elevation showing so

much of a United States Army rifle, model of 1903, as will illustrate the application of our invention thereto, the wooden stock being broken away to disclose the reenforcing plates and rivets.

Fig. 2 is a plan view, the rifle action being omitted; and

Fig. 3 is a detail cross section on the line 3—3, Fig. 1.

10 In carrying out our method and reenforcing means, vertical cuts, slots, or kerfs are made through the stock by sawing or in any other manner.

15 The next step is to insert in these kerfs the vertically arranged plates 1 which are preferably of metal, steel being best adapted for the purpose.

20 Plates 1 are of a thickness or gauge adapting them to snugly fit the walls of the previously made cuts, slots, or kerfs and they are of the general form shown in Fig. 1 when used in connection with the particular firearm illustrated but it is to be understood that shape and position of these plates may 25 be changed according to the design of the arm with which they are used. As illustrated, the front edges of the plates 1 abut the rear end of the magazine 2, the magazine being accommodated in the vertical 30 opening 7 (Fig. 2) in the stock. This arrangement assists in taking up the recoil in the event that the recoil shoulder (not shown) at the forward end of the receiver 3 does not fit tightly against the edge of the 35 recess in the stock. In rifles of other design, the plates 1 may be arranged to abut any other part of the receiver in such manner as to take up the recoil. By thus positioning the plates 1, the recoil is distributed through 40 the plates and their fastenings 5, over a large area of the stock, thus minimizing the chances of the stock splitting from the force of the recoil.

45 Reference to Fig. 3 discloses the manner in which the upper edges of the forward parts of the plates 1 abut the lower part of the receiver 3 and this figure also shows the manner in which the lower edges of the forward parts of the plates 1 abut opposite sides of the guard 4.

50 To the rear of the receiver and guard, the plates 1 lie flush with the upper and lower parts of the wood of the stock.

To fasten the plates 1 together and to 55 afford additional means for assuming and distributing the force of the recoil as well as strengthening and stiffening the weakest part of the stock, fastenings 5 pass through the stock and through holes in the plates 1.

60 Having inserted the plates 1 in the cuts or kerfs as previously described, the stock and the plates are then drilled and the fastenings 5 next inserted. The fastenings 5 are preferably rivets which are provided with heads, countersunk in the stock as shown in Fig. 2.

The number of the fastenings 5 may vary but at least some these fastenings are preferably so placed that when the rifle action is assembled to the stock, they tend to firmly anchor the plates to the rifle action. To that end, one of the rivets may be placed immediately to the rear of the guard screw 6 and another just to the rear of the magazine 2 because at these points the wood of the stock is compressed by the guard screws between the receiver 3 and the guard 4 at right angles to the extent of the rivets 5.

Among the advantages obtained by our invention are the following: The recoil is distributed through the plates and rivets 80 over a relatively large area and chances of splitting the stock are minimized; the stock is strengthened at its weakest point and it is possible to use fancy curly grained wood and certain shapes of grip which would otherwise be too weak to withstand the recoil; the stock is stiffened at the point where it needs to be rigid in order to afford the greatest accuracy in the use of the firearm.

90 The reenforcing of the stock prevents breakage from the hard usage to which a rifle is subjected in the army, such as bayonet work and hand-to-hand fighting in which the rifle might be used as a club; and also the rough usage in big game hunting. 95

We claim:

1. The method of reenforcing a gun stock consisting in providing a cut therein terminating short of the butt of the stock, inserting a reenforcing element in said cut, 100 and mechanically securing said element to the stock by a fastening device extending crosswise of the stock.

2. The method of reenforcing a gun stock consisting in making a vertical cut or slot 105 therein terminating short of the butt of the stock, inserting a flat reenforcing element in said slot, and securing said element to the stock by a fastening device.

3. The method of reenforcing a gun stock 110 consisting in providing parallel vertical cuts therein, inserting reenforcing plates in said cuts, and securing said plates to the stock by a fastening device.

4. The method of reenforcing a gun stock 115 consisting in providing parallel vertical cuts therein, inserting reenforcing plates in said cuts, and securing said plates to the stock by transversely arranged fastenings passing through the plates and the stock.

5. A firearm stock having an internal shoulder and provided with an internal 120 reenforcing element whose rearward end terminates in the region of the shoulder.

6. A firearm stock provided with an internal 125 reenforcing plate extending lengthwise thereof and having an abutment for said plate located inwardly from the butt of the stock.

7. A firearm stock provided with an inter- 130

nal vertically arranged reenforcing plate extending lengthwise thereof, and a cross-connection which secures the plate to the stock.

5. 8. A firearm stock provided with a plurality of internal vertical reenforcing plates connected to the stock.

9. A firearm stock provided with a plurality of internal vertical reenforcing plates, 10 and fastenings arranged transversely to said plates and connecting them to the stock.

10. In a firearm, the combination with a part of the rifle action and the stock, of a reenforcing element interposed between the 15 stock and the action and abutting a metal part of the firearm and fastened to the stock.

11. In a firearm, the combination with the block of the action thereof, and the stock, of a reenforcing element contained within 20 the stock and fastened thereto whose forward end abuts a metal part of the firearm.

12. In a firearm, the combination with the magazine, and the stock thereof, of a reenforcing element whose forward edge

abuts the magazine and whose rearward edge 25 abuts the stock.

13. In a firearm, the combination with the magazine, and the stock thereof, of a reenforcing element whose forward edge abuts the magazine and whose rearward edge 30 abuts the stock, and cross connections fastening the element to the stock.

14. In a firearm, the combination with the receiver, the magazine, the guard, and the stock, of a pair of reenforcing plates whose 35 forward edges abut the magazine and which flank the receiver and the guard and whose rearward edges abut the stock, and cross fastenings extending through the plates and securing them to the stock, certain ones of 40 said fastenings being located in the region of the rear of the magazine and of the guard fastening.

In testimony whereof we affix our signatures.

ARTHUR G. SCHLOSSER.
WILMER N. ELTON.
